WELL-PIPE HEAD.

Application filed December 18, 1922. Serial No. 607,722.

This invention relates to heads for well pipes; and although the invention is not restricted to oil wells and can be used on gas and water wells, its largest use at present, is in connection with oil and gas wells and accordingly the following description will be given in that connection.

In oil and gas wells it has been common to use a number of concentric well pipes. 10 For instance, there is always at least one string of casing and then a tubing inside the casing; and in the majority of instances there are several strings of casing one within the other with the tubing inside the innermost casing string. Thus for instance, there may be three strings of casing and a tubing. It is necessary to cap the upper ends of the casing strings to make the well gas tight, and in order to take off the gas. 20 These caps or heads are usually arranged to support the inner string and tubing on the outer string; but it is not in this difficulty of supporting the inner pipes but in the difficulty of making a simple arrangement 25 that will make a tight joint between the various pipes that our invention resides. Heretofore it has been common to use packings around the pipes and this has entailed complications and has made the well head un- 30 safe and liable to blow out. It is a general object of our invention to provide a well head that is simple, of small dimensions, makes a gas tight joint without the use of packing and is easily applied. In our de- 35 vice we form all the joints by screw threads; and the device is so constructed and assem- bled that the joints may be very easily screwed up tight. Our invention in one of 40 its forms also provides facilities for the use of slips for supporting an inner string of pipe, for instance, the tubing, while being lowered into or taken out of the well.

Other objects and the features and ad- 45 vantages of our invention will be best un- derstood from the following detailed speci- fication wherein we explain preferred forms of our device, reference for this purpose be- ing had to the accompanying drawings

wherein—

50 Fig. 1 is a vertical section showing one form of our device;

Fig. 2 is a cross section on line 2—2 of Fig. 1;

55 Fig. 3 is a longitudinal section showing another form of our device;

Fig. 4 is a cross section on line 4—4 of Fig. 3; and

Fig. 5 is a longitudinal section showing how our devices may be applied to several 60 strings of pipe.

Referring first to Figs. 1 and 2 I show therein an outer pipe A and an inner pipe B. These may be taken to illustrate pipes of any diameter; for instance, they may illustrate either a casing or tubing or may illustrate two sizes of casing. A collar 10 is screwed upon the upper end of outer pipe A and into this collar is screwed the seat member C of the joint forming device, the other seat member D of which surrounds inner pipe D and is screwed tightly to it. In this particular case the upper threaded end 11 of the inner pipe is shown as being screwed upwardly through member D and projecting above it for making any connec- 70 tions that may be desired. Member D has a lower flat surface 12 that rests on the upper flat surface 13 of member C; and member C has a conical or tapering bore 14 into which a conical flange or petticoat 15 of member D fits. The action of these two interengag- 75 ing parts is to accurately center inner pipe B with relation to the outer pipe and also center member D accurately on member C. 80 On members C and D there is cut a continu- 85 ous tapered thread as shown at 16 and 17; and a collar 18 with an interior tapered thread is screwed down over the threads 16 and 17, these threads being so fitted that when collar 18 is in the position shown in 90 Fig. 1 its threads are tight on threads 16 and 17 with the result that collar 18 not only holds member D securely on member C but also forms a fluid tight joint with 95 bore members C and D and, the joining of member C with outer pipe A being by tight threaded joints, and that of member D with inner pipe B being by tight threaded joints, the structure that we have described, when 100 thus assembled, forms a tight joint between the two pipes, and at the same time securely holds the pipes anchored one with relation to the other.

The threads 16 and 17 are cut as one con- 105 tinuous tapered thread. This may be done by assembling the parts C and D for the purpose of cutting the thread. To locate parts C and D with reference to each other, rotatively, we may employ any suitable means, such as a pin 20 on part D extending

into a hole in part C. Once the two threads 16 and 17 are cut with the parts in this definite relation, then by putting pin 30 into its hole the threads will always be in proper relation for collar 18 to be threaded on. The parts are very easily assembled in the position shown in Fig. 1. Member C is set upon the outer pipe A and member D set upon inner pipe B. Then inner pipe B 10 is lowered so that pin 20 goes into its hole in member C and then collar 18 is screwed down tightly.

To take off gas between the two pipes we provide an opening at 31 in member C to 15 which an outlet pipe 32 may be connected.

In the form shown in Figs. 3 and 4 the member C¹ is not provided with tapered bore 14 and member D¹ is correspondingly not provided with the sleeve 15. Member D¹ 20 here rests only on the upper surface of member C¹; and then we use three pins 20^a setting in holes, member C¹, these pins and holes being unequally spaced so that member D¹ can only be set down on member C¹ in a 25 certain position, and the three pins at the same time center member D¹ accurately on member C¹. Any equivalent means may be used; for instance, two pins 20^a not diametrically opposite each other will do, but three 30 are preferred.

It will be noted that the only substantial difference between the forms of Figs. 1 and 3 is the omission of the tapered parts 14 and 15. In the form shown in Fig. 1 the tapered bore 14 may be used to receive slips to hold the inner pipe while it is being lowered into or raised out of the well. This provision is particularly advantageous with relation to a tubing; and so, although either the form of Fig. 1 or that of Fig. 3 may be used between different strings of pipe, we prefer to use the form of Fig. 3 between the different strings of casing and the form of Fig. 1 between the casing and tubing.

45 Thus, in Fig. 5 we show a preferred assembly to cap three strings of casing and a tubing. Here there is an outermost casing A², a next inner string of casing A¹; then the innermost casing string A and a tubing B¹. Casing string A² has at its upper end a collar 10 and into this collar the member C¹ is set. This member C¹ is of the type described in connection with Figs. 3 and 4. On top this member C¹ there is a member D² secured to member C¹ by the collar 18 in the manner hereinbefore described, with pins 20^a to align member D² on member C¹ as described in connection with Figs. 3 and 4. Member D² is formed, not like member D¹ of Fig. 3, but 55 more like member C¹ of Fig. 5; being substantially a duplicate of C¹ except that C¹ is formed at its lower end to screw into collar 10, while D² is formed at its lower end to rest on C¹ and to be secured thereto by tapered collar 18. Casing A¹ screws into the

upper end of member D² and its end is in the assembled device, flush with the upper end surface 13^a of D². When the parts of the head are being put together, member D² will be run down on a comparatively long 70 thread on pipe A¹ to locate D² on the pipe accurately, and then the upper end of pipe A¹ that projects above D² will be cut off flush.

Next above member D² is another member 75 D³ exactly like D² except for size. D³ rests on upper surface 13^a of D², is secured to D² by taper collar 18, and carries pipe A just as D² carries pipe A¹; except that pipe A extends above D³ to take collar 10^a. In collar 80 10^a is mounted member C, of the type of joint shown in Fig. 1, to support tubing B¹. This needs no added description as it has been covered in detail in connection with Fig. 1; the only difference being that tubing 85 B¹ may be screwed into the lower part of member D, and a discharge pipe 30 screwed into the upper part of that member, instead of running tubing B¹ clear through and above D.

90 It will be seen that the joints formed between the three casing strings are specifically of the type heretofore described in connection with Figs. 3 and 4; the only difference being that in this case the members D² and D³ not only directly support casing strings A¹ and A (like member D¹ does in Fig. 3) but also have an upper extension to take the next upper member that supports the next inner casing string. And, in practice, we may prefer to use such elements or members as D², D³, instead of the simpler ones shown at D and D¹ because D², D³ can be used in all situations (to head one or more strings of pipe inside an outer string) whereas D and D¹ are limited to use either with a single string inside an outer string or to the last inner string of a series. Thus, although D or D¹ could be used in Fig. 5 in place of D³ 100 we show the standard form D³ there although its upper tapered connecting threads 17 and its pin holes 20^b are not in actual use. 105 In the form of D² or D³ the offset at 32^a allows the gas between strings to reach the gas pipes 32.

110 We have thus shown how the form of Figs. 3 and 4 may be duplicated to support more than one casing string inside an outermost casing string; and it will be apparent from this how the form of Figs. 1 and 2 may be duplicated to so support a plurality of inner casing strings within an outermost casing string. In practice we have found it unnecessary to provide slip-ways (the conical bore 14) for the casing strings; but if those should be desired for the casing strings the form shown in Figs. 1 and 2 may be used in place of that shown in Figs. 3 and 4.

115 But for supporting the tubing B¹ we prefer to use the form shown in Figs. 1 and 2. 120

Accordingly, the inner casing string A has the collar 10^a at its upper end where it projects above member D^b, and in this collar the member C is mounted; and in and on member C the member D is mounted and held by collar 18, all as described in connection with Figs. 1 and 2. In this instance, however, instead of extending tubing B¹ above member D, we may screw tubing B¹ into the lower part of member D and then connect the discharge pipe 30 into the upper end of member D.

It will be noted that our device uses no packings; in practice one of its most advantageous features is that it does not require the use of any packing glands or the like. Its screw threaded joints provide at one and the same time fluid tight connection and secure mountings for the different pipes. Furthermore, the device is very easily and quickly assembled; and it makes a finished well head of minimum height. It also provides facilities for the use of pipe supporting slips where desired.

Having described a preferred form of our invention, we claim:

1. In a device of the character described, a connecting element embodying an annular body having portions of different external diameters, an exterior tapered thread around its portion of smaller diameter, a seating surface with a registry pin hole at its smaller end, an exterior tapered thread around its portion of larger diameter, a seating surface with a registry pin at its larger

end; an internal screw thread at its smaller end to receive a pipe, and an internal offset providing a passage leading from the larger end toward the smaller end and communicating with a gas outlet through the body wall.

2. In a device for connecting three or more nested concentric pipes, an annular seating member of different diameters at its opposite ends, the bore of said member being internally threaded to take external threads provided on a given intermediate pipe, second and third annular seating members adapted to engage the opposite ends of the first mentioned seating member, each of said second and third members being of two external diameters and one of them having an internally threaded bore to take external threads provided on one of the pipes which is adjacent the given pipe, means for connecting the other adjacent pipe to the other of the second or third seating members, the opposite ends of said first mentioned seating member and the associated engaging ends of the second and third seating members having continuously threaded portions; and continuously threaded collars adapted threadably to connect said seating members at their engaging ends.

In witness that we claim the foregoing we have hereunto subscribed our names this 7th day of December 1922.
